UNITED STATES PATENT OFFICE.

HARRY P. FAIRCHILD, OF NEW YORK, N. Y.

DESIGN FOR A MATCH-BOX.

SPECIFICATION forming part of Design No. 19,910, dated June 17, 1890.

Application filed May 15, 1890. Serial No. 351,975. Term of patent 3½ years.

To all whom it may concern:

Be it known that I, HARRY P. FAIRCHILD, a citizen of the United States; residing at New York, in the county of New York and State of New York, have invented a new Design for Match-Boxes, of which the following is a specification.

My invention consists in a design for match-boxes of the kind carried in the pocket.

10 The accompanying print is a face or front view of a box embodying my design.

The design consists, first, of the shape or outline of the box as viewed from the front or face. As shown, the central portion of its edges are swelled or expanded outward at each side, as are also the central portions of the two ends at top and bottom. The four corners which unite the sides and ends of the box consist of an ornamental scroll, the outer 15 boundary of which is circular, there being an incurred indentation at the points where they unite to the ends and sides, the latter being curved inward in like manner at the points of union with the curved corners, as shown, thus imparting to the box a rich and ornamental appearance.

The second feature of my design consists in the ornamentation of the front or face of the box. This ornamentation consists of a series of lines arranged diagonally across the surface, and on each of these lines is arranged a series of figures representing the leaves of a plant having their ends curled or curved in the form of a scroll. The whole is surrounded by an ornamental border extending along the edge all around, as shown, though this may be omitted without materially changing this part of the design, which consists of the diagonal lines and the set figures arranged thereon, substantially as shown.

What I claim is—

1. The outline shape or design for a match-box, substantially as shown and described.
2. The design for face ornamentation, consisting of the diagonal lines with the figures arranged thereon, substantially as shown.

20 In witness whereof I hereunto set my hand in the presence of two witnesses.

HARRY P. FAIRCHILD.
